UNITED STATES PATENT OFFICE.

CHARLES K. JONES, OF KANSAS CITY, MISSOURI.

PRINTING-TELEGRAPH.

982,275.

Specification of Letters Patent. Patented Jan. 24, 1911.

Application filed September 14, 1909. Serial No. 517,742.

To all whom it may concern:

Be it known that I, CHARLES K. JONES, a citizen of the United States, residing at Kansas City, in the county of Jackson and 5 State of Missouri, have invented certain new and useful Improvements in Printing-Telegraphs; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specifi- 15 cation.

My invention relates to printing-telegraphs; and it consists in a novel arrangement of circuit-forming relays, selecting-relays and associated devices whereby by the 20 operation of a single main-line circuit controlling the selective action of the said relays any one of a plurality of type-bars or printing devices may be actuated at will and other actuations be accomplished for vari- 25 ous operating purposes.

My invention consists of apparatus whereby automatic protection is provided to the receiving instrument against destruction by a powerful electric energy such as is neces- 30 sarily used in an instrument of this character and thereby making it possible to operate my invention in small private offices and in places of ordinary business for the receipt of private telegraphic correspond- 35 ence, stock or market quotations, bulletins, press despatches, etc.; of apparatus whereby the instrument may be adjusted to correspond with the speed of the transmitter; of apparatus whereby a plurality of sets of 40 printing or operating-magnets are available for any purpose desired, so that one set may be used for the small letters, figures and punctuation-marks and operating purposes and another set for the capital letters, fig- 45 ures, punctuation-marks and operating pur- 50 poses and another set for italic letters and other purposes; and generally my invention consists in the novel features hereinafter set forth, and particularly pointed out in the claims.

The objects of my invention are to improve and simplify printing-telegraph systems and apparatus, to simplify and improve the operation of printers employing

type-bars or similar printing-devices for the 55 several characters; to provide apparatus whereby the ordinary dot and dash code of telegraphy may be received and translated into printed characters or be used for any other purposes desired; to provide a receiv- 60 ing printing instrument adapted for operation by any type of transmitter ranging from the slowest to the highest speed in- strument.

I have illustrated three sets of printing 65 and operating-magnets which are controlled by what will be designated as "circuit- 70 making relays", and it will be obvious from a further understanding of the method of operation that these sets may be increased 75 or diminished as may be desired by following out the same method illustrated and I claim the privilege of so doing.

I will now proceed to describe my in- 75 vention with reference to the accompanying drawings, in which one embodiment of the invention is illustrated and will then point out the novel features in claims.

In the said drawings, Figure 1 is a dia- 80 gram showing an ordinary hand-manipu- 85 lated telegraph-key for a transmitter and the various relays, type-bar magnets, operating-magnets, and circuits of the corresponding receiving instrument or printer. Fig. 2, illustrates one form of type-bar 85 mechanism adapted to be actuated by type- 90 bar magnets. Fig. 3, is a view in side ele- vation of one of the selecting-relays. Fig. 4, is a horizontal sectional view on the line A—A, of Fig. 3.

In this system I employ for the transmis- 95 sion of the messages current pulses, but said pulses vary in length, the short pulses repre- 100 senting dots and the long pulses represent- ing dashes, and these pulses are usually, but not necessarily, alternately of opposite direc- tions. For transmitting the characters of the English alphabet I may employ from one to six dots or dashes, or combinations of dots and dashes. This number of dots and dashes would give ample operating-magnets, which would be sixty-four magnets, permitting the transmission of the alphabet, nu- 105 mers, punctuation-marks and for the operation of spacing, carriage-return and shift mechanism, such as are used on various well-known electrical-type-writers and leaving a margin for any other purposes that may be

desired. For transmitting a less number of characters than are contained in the alphabet I may employ a fewer number of dots and dashes and for transmitting a greater number of characters than are provided for 5 herein I may employ more than six dots or dashes or combinations of dots and dashes.

In the accompanying drawings I have 10 illustrated apparatus for receiving and printing adapted for operation by a code 15 consisting of a maximum number of four dots or four dashes or combinations of this number of dots and dashes, this being done for the purpose of obviating an unnecessary lengthy description, as it is clearly obvious 20 that the system may be extended to any limit desired by following out the same method herein pursued.

Referring now to the drawings and at first 25 to Fig. 1, the said figure shows an ordinary telegraph-hand-manipulated key for a transmitter, said type of transmitter being chosen for illustration on account of its simplicity as compared with the Wheatstone transmitter or other types of complicated transmitters, for be it understood that the receiving apparatus illustrated herein is adapted for operation by any type of transmitter, all that is necessary being that the main-line relay 30 be connected to the receiving instrument as illustrated, viz. through the opposing-contacts and having the armature connected to one pole of a battery and the other pole of said battery connected to ground, so that the pulses received by the main-line relay will 35 be relayed to the receiver, and I claim the privilege of so operating, the transmitter being no part of my invention, but simply used in the illustration for the purpose of explaining more fully the operation of the receiver or printer; the operation of the transmitter will be described more fully herein-after; and a receiving instrument comprising 40 a main-line relay 1, and a plurality of relays hereinafter described. The receiving instrument and transmitter are connected by a line-wire 2. At the transmitting end this line-wire passes through contacts of an ordinary pole-changer 3, forming a part of the 45 transmitter and operated by a local circuit controlled by contacts of the transmitter. At the receiving end the line-wire 2, passes through main-line relay 1, which in the instance shown is a polar relay, to ground. 50 Main-line relay 1, controls two local circuits 4 and 5, connected to opposing contact-points of the main-line relay. A battery 6, or other suitable source of electric energy is connected to ground and to the armature of 55 main-line relay 1. One or the other of circuits 4 and 5 is completed through battery 6 according as the said armature of relay 1, is in contact with the right-hand or left-hand contacts of said relay, however this is not 60 true until the first pulse actuates the arma- 65

ture of main-line relay 1 into the abnormal position, this being for the purpose of opening a circuit between battery 6 and the instrument intervening between one complete operation of a characteristic signal and the beginning of the succeeding characteristic signal. Circuit 5 is formed by the first operation of main-line relay 1, which operates relay 24 (designated as "entrance-relay") 70 into the abnormal position and relay 24 remains in such position until relay 22 is operated which operation completes a circuit passing through the restoring-coils of relay 24 and thus restoring it to normal position; the operation of relay 22 also completes the 75 print-circuit which will be explained hereinafter. A condenser 8, is connected across the contact-points of the relay 1, to reduce 80 sparking.

Referring now to the transmitter, the same 85 as shown in the drawings, consists of an ordinary hand-manipulated telegraph-key 9, adapted for engagement with contact 10, which is connected to magnet 3 of the pole-changer, thence to battery 11 by conductor, 90 and by conductor from battery 11 returning to key 9; key 9 is held normally in one position by spring 14. Magnet 3 controls the spring-held armature of an ordinary pole-changer, which pole-changer in its operation 95 places alternately on the line-circuit sources of electric energy or batteries 12 and 13 of opposite polarity, thereby producing in the line-conductor 2, current pulses of opposite 100 polarity.

The function of the entrance-relay 24, is to 105 protect the parts from injury resulting from a prolonged energization from battery 6, intervening between characteristic signals.

On account of a thorough description being made explaining the operation of the instrument in a number of characteristic signals which follow, a brief description of the instrument will here suffice: The receiving instrument consists of a number of 110 polar relays having restoring-coils and a number of neutral relays said polar and neutral relays being designated as "circuit-forming relays"; a group of polar relays having restoring-coils being designated as 115 "circuit-making relays"; and a number of neutral relays being designated as "selecting-relays". The receiving instrument as illustrated is in the normal or open-circuit position with no electric current into its parts 120 in perceptible activity except to the main-line relay 1 from battery 12. There are four selecting-relays corresponding to the maximum number of pulses composing the code herein used and these relays are not 125 operated except by the long or dash pulses. For purposes of description the selecting-relays will be designated as in clusters on account of said relays of the second, third and fourth clusters having a plurality of 130

contact-points with spring-plates for engagement therewith as illustrated in Figs. 3 and 4. The relay of the first cluster is an ordinary neutral relay having two contact-points, the relay of the second cluster has four contact-points and four spring-plates for engagement therewith, the relay of the third cluster has eight contact-points and eight spring-plates for engagement therewith, and the relay of the fourth cluster has sixteen contact-points and sixteen spring-plates for engagement therewith. The contact-points of the selecting-relays are connected one to another as follows: One of the contact-points of the relay of the first cluster is connected by conductors to each contact-point of two of the contact-points of the relay of the second cluster, the other contact-point of the relay of the first cluster is connected by conductors similarly with the remaining two contact-points of the relay of the second cluster, the four spring-plates of the relay of the second cluster are connected by conductors in a similar manner to the contact-points of the relay of the third cluster, and in like manner the remaining clusters are connected one to another, the relay of the fourth cluster having therefore sixteen contact-points connected by conductors to the preceding cluster, and sixteen spring-plates remaining are connected by conductors to their respective printing or operating-magnets of a set which is designated as "set 25", the other terminals of said magnets are connected to a multiple lead 103, thence by wire 104, through the armature of circuit-making relay 29, wire 106, through armature of circuit-making relay 28 and to ground at 108. Three of the spring-plates of the relay of the last cluster are connected in circuits passing through the coils of their respective circuit-making relays 28, 29, 30 and 31, and to ground, the object of which being to control the sets 25, 26 and 27. The printing and operating-magnets in set 26 are connected by conductors to their respective spring-plates of the relay of the last cluster and the other terminals of said magnets are connected to a multiple lead 123, to contact-point of circuit-making relay 30, the armature of relay 30 connected by conductor 124 to a contact of relay 28, the armature of circuit-making relay 28 is connected to wire 107 leading to ground at 108. The printing and operating magnets of set 27 are connected in a similar manner to their respective spring-plates of the relay of the last cluster and the other terminals of said magnets are connected to a multiple lead 132 and thence to a contact-point of circuit-making relay 31, the armature of relay 31 is connected to ground at 133. Two printing or operating-magnets only are shown in each of the sets 26 and 27, but it will be

understood that there are circuits available for operating thirteen of such magnets in each of said sets and the claims will therefore be drawn accordingly.

It will be noted that the circuits available for operation by the selecting-relays are in geometrical progression. The printing and operating-magnets in set 25 are illustrated as being normally in circuit with contacts of said selecting-relays of the last cluster and if it be desired to cut out of circuit set 25 and to cut into circuit set 26, it will be necessary to operate the characteristic signal controlling the operation of circuit-making relay 28, which will consummate the purpose by opening one multiple lead and making another multiple lead good to ground through circuits controlled by the circuit-making relays; if it be desired to cut out of circuit the set 26 and to cut into circuit the set 27, it will be necessary to operate the characteristic signal controlling the operation of circuit-making relays 29, 30 and 31, which relays are connected in electrical series for simultaneous operation and the desire is consummated by opening one multiple lead while another multiple lead is made good to ground; to restore the sets to their normal position it is necessary to operate the characteristic signal controlling the operation of the circuit-making relays 28, 29, 30 and 31, which relays are connected in electrical series for simultaneous operation and the purpose is accomplished by opening two multiple leads while the multiple lead of set 25 is made good to ground.

The magnets comprising the sets 25, 26 and 27, may be termed type-bar and operating-magnets or printing and operating-magnets, though as hereinafter shown, certain of these magnets may operate shift mechanism, space mechanism, carriage-returning mechanism, or the like.

Each selecting-relay is connected in a circuit controlled by a corresponding circuit-forming relay and each such circuit is adapted for operation successively, by the dash or long pulses. For convenience of description we will designate the four circuit-forming relays which control the four selecting-relays as "the dash-relay," or "dash-relays."

There are two sets of neutral relays comprising the circuit-forming relays, which sets comprise relays adapted for operation successively, the last relay in each set being operated only by the dashes or long pulses. A switch 57, in one set, and switch 77, in the other set are adapted for engagement with the contacts 143 and 144 and 143' and 144' respectively, for the purpose of cutting out of circuit one or more of the relays in said sets, thereby adapting the receiving instrument to a faster speed. Should a slower speed than is herein illustrated be desired then it will be necessary to increase the num-

ber of the relays comprising said sets, and I claim the privilege of so doing. The two sets of neutral relays are controlled by the main-line relay, one set being controlled by one contact and the other set being controlled by the other contact; one set embracing relay 17, is for completing the circuits controlling the operation of the dash relays 109, 110, 111 and 63 and the last-named relays control the selecting-relays as previously stated; the other set of neutral circuit-forming relays is for the purpose of completing the print-circuit and the restoration-circuit, relays 22 and 23, designated as the "print-relay" and the "restoring-relay," when operated accomplishing this purpose. It will therefore be obvious that a print and restoration may be effected with the second, fourth, sixth or eighth pulse operated the requirement being that the transmitter remain in the normal position long enough for the relays 18 to 23 inclusive to be operated successively.

Two printing or operating-magnets may be controlled by two pulses operated by the main-line relay said magnets being in set 25; two magnets in set 26 and two of said magnets in set 27 may be controlled by two pulses operated by the main-line relay, but as previously explained the multiple leads controlling the circuits of the sets must be changed by the operation of the circuit-making relays before the magnets in sets 26 and 27 can be operated; similarly, two others of said magnets may be controlled by the operation of four pulses by the main-line relay; a total of sixteen selecting-circuits are available for operation in set 25 by the operation of the code of two to eight pulses by the main-line relay. The dash-completing relay 17, is operated by a long pulse or dash operated by the main-line relay in the first, third, fifth and seventh pulses. The restoration leaves the various relays in position for the first pulse operated by the main-line relay 1, beginning a characteristic signal; if the first pulse be a dot or short pulse the polar relays of the circuit-forming relays are not operated, but if the first pulse be a dash then relay 17 is operated thus completing a circuit which passes through the armature of relay 39 via conductor to a plate contact on the armature of relay 40, but said plate is insulated from said armature, thence to contact of relay 40, thence through the coils of the first dash-relay 109, and to ground and thus operating said dash-relay; the operation of the dash-relay 109 completes a circuit through the contacts of relay 109 thus operating the selecting-relay of the first cluster and the relay 109 and the said selecting-relay will remain in such position until the restoration takes place; the second pulse if a short pulse will not operate the extreme relays 22 and 23 but will operate

polar relays 39 and 40 in a circuit passing through the coils of said relays and to ground and thereby severing a circuit by the operation of relay 40 through which relay 109 was operated, and also forming a circuit through the armature of relay 40 and its lower contact for the operation of relay 43 by the third pulse, and the operation of relay 39 forming a circuit through its other contact whereby the third pulse may operate the second dash-relay 110, if perchance there be a dash occurring in the third pulse; the third pulse operated will operate polar relay 43, in a circuit via conductor 41, through the armature of polar relay 40 and its lower contact, through the coils of relay 43 and to ground, and thus forming a circuit through the contacts of relay 43 for the operation of the fourth pulse; if the third pulse be a dash then relay 17 is operated thereby completing a circuit from wire 60, through the armature of polar relay 39 and its lower contact, thence by conductor through the contact and through the plate on the armature of relay 46, but said plate is insulated from said armature, thence by conductor through the coils of the second dash-relay 110, and to ground, and thus operating the second dash-relay, which second dash-relay will in turn complete a circuit through its contact which will operate the selecting-relay of the second cluster; the fourth pulse will operate relays 46 and 47, by a circuit passing through the armature of relay 43 and its lower contact and through the coils of relays 46 and 47, to ground, thus severing the circuit through which the second dash-relay 110 was operated, the circuit being opened by the armature of relay 46 leaving the upper contact, the change of position of the armature of relay 46 also forming a circuit for the operation of relay 50 by the fifth pulse, the operation of relay 47 forming a circuit through its contacts for the operation of relay 111, the third dash relay, by the fifth pulse; the operation of the fifth pulse will operate polar relay 50 in a circuit via wires 41 and 48 through the armature of relay 46 and through the coils of relay 50 to ground, thus forming a circuit through the contacts of relay 50 for the operation of the sixth pulse; if the fifth pulse be a dash then relay 17 is operated thus completing a circuit via conductor 60, through the contacts and armature of relay 47, through the upper contact and the plate on the armature of relay 54, said plate insulated from said armature, through the coils of relay 111, the third dash-relay, and to ground, thus operating the third dash relay, which in turn will operate the selecting-relay in the third cluster; the sixth pulse operates polar relays 54 and 55 in a circuit via wire 38, through the armature and upper contact of relay 51, through the arma- 130

ture and lower contact of relay 50, and through the coils of relays 54 and 55 and to ground, thus severing the circuit through which the third dash was effected said opening occurring when the armature of relay 54 leaves its upper contact, and when said armature makes its lower contact, a circuit is formed for the operation of relay 51 by the seventh pulse, the operation of relay 55 5 forms a circuit for the operation of the fourth dash-relay if there be one occurring in the seventh pulse; the seventh pulse operates relay 51 in a circuit passing through the armature of relay 54 and through the 10 coils of relay 51 and to ground, thus severing through the contacts of relay 51, the circuit which operated the relays 54 and 55 in the sixth pulse and effecting a saving in operating current; if the seventh pulse be 15 a dash then relay 17 is operated and a completing circuit is operated from ground 7, through battery 6 through armature of relay 1, wire 4, through the armatures of relays 15, 16 and 17 to wire 60, it will be understood from what has previously been 20 stated that the relays 15, 16 and 17 are operated successively thus forming a circuit through their contacts to wire 60, from wire 60 to wire 61, through the armature of relay 55, wire 62 and through the coils of the 25 fourth dash-relay 63 to ground, thus operating relay 63, which in turn completes a circuit through its contacts which operates the fourth cluster relay in a circuit from ground 64, through multiple lead 66, through the armature and contact of relay 63, wire 67, through the coils of relay 68 and to ground at 69; if all the four pulses 30 operated be dashes then all the polar relays comprising the circuit-forming relays will now be in the abnormal position; the eighth and final pulse comprising the code of operation will energize the magnets of polar relays 39, 40, 46 and 47, but there will be 35 no actuation of the armatures of said relays for the reason that these armatures are already in the abnormal position, and said energization will continue until the entrance-relay is operated which will break the connection to battery 6 and deenergization will 40 follow; the eighth pulse will operate the neutral relay set comprising relays 18 to 23, inclusive, and the operation of the final relays 22 and 23, which operation occurs successively, will cause a print to ensue or cause 45 the energization of an operating-magnet from a circuit starting from ground at 89, through the coils of entrance relays 24, thereby restoring entrance-relay 24 to normal position, wire 90, through battery 91, through the contacts of relay 22, wire 92, through the armature of the selecting-relay of the first cluster and through the contacts 50 of said relay and through the contacts of others of the selecting-relays to the selected 55 printing or operating-magnet, through multiple lead 103, wire 104, through armature of circuit-making relay 29 to wire 106, through armature of circuit-making relay 28 and to ground, thus energizing said selected printing or operating-magnet; the operation of relay 23 which follows very quickly the operation of relay 22, completes a circuit through the restoring-coils of all the polar relays except the entrance relay 75 and the parts are restored to normal position.

The operation of this apparatus is as follows: supposing, for example, that the message to be transmitted consists of three dots 80 followed by a dash; the transmitter 9 is depressed or closed so that it makes contact with 10, and then said transmitter is released so that it will be carried back to the normal position by spring 14; this will energize magnet 3, and the pole-changer actuated so that battery 13 is placed to the line and circuit 4 will be completed to relay 15. The first operation being a dot or short pulse, the armature of the main-line relay 1, 85 does not remain in contact with circuit 4 long enough for the operation of relays 16 and 17 to take place; another circuit 32 is connected to circuit 4 passing through an adjustable resistance 33 thence through the 90 coils of polar relay 24, the entrance-relay, to ground, thus effecting a circuit whereby the main-line relay 1, may cause operations of the various parts when its armature is returned to the normal position after the first 100 pulse; when the armature of main-line relay 1 is actuated to the normal position a circuit is made as follows: wire 5, armature of polar relay 24, wire 34, relay 18 to ground; 105 as the relay 1 will not remain in the normal position long the remainder of the relays 19, 20, 21, etc. embracing the neutral relay set will not be operated; a branch circuit 35 is connected with wire 34 which leads to the armature of relay 18; another branch circuit 110 is connected to wire 35, it being conductor 36, thence to wire 38, through the coils of polar relays 39 and 40 to ground, thus actuating the armatures of relays 39 and 40 to 115 the abnormal position and they will remain so until all the parts are restored to normal position. The next operation being a dot, the transmitter is operated the same as with the first dot and the main-line relay 1 is operated into the abnormal position and the 120 result will be the same as described in the first dot but there will be no further actuation of the entrance-relay 24 until the parts are restored to normal; an additional circuit will now be operated as follows: connected with wire 4 is a branch wire 41, leading to the armature of polar relay 40, thence to wire 42 and through the coils of polar relay 43 to ground, thus actuating the armature of 125 polar relay 43 into the abnormal position. 130

The second dot being completed the armature of main-line relay 1 is actuated into the normal position and the following circuits are made: relay 18, is operated as in the previous operation and in addition thereto a circuit is made from wire 34 to wire 35, wire 36, wire 38, wire 44, armature of polar relay 43 to wire 45, through the coils of polar relays 46 and 47 to ground, thus operating relays 46 and 47 into the abnormal position.

The third dot calls for the same operation of the transmitter as the previous dots and the operations on the parts will be the same as the previous ones, except that the circuit will now run from wire 4 to wire 41, wire 48, through armature of relay 46, wire 49, through the coils of relay 50 and to ground, thus operating relay 50. The third dot being completed the armature of the main-line relay 1, is operated into the normal position with the following result: in addition to the operation of relay 18, the circuit goes from wire 34 to wire 35, to wire 36, wire 38, armature of relay 51, wire 52, armature of relay 50, wire 53, through the coils of relays 54 and 55 to ground, thus operating relays 54 and 55. The next transmission being a dash, the transmitter is held in contact with 10, for a longer period than for the dot and the following operations result: relay 15 is operated thus causing another circuit to be made from wire 4, through the armature of relay 15 to wire 56, switch 57, wire 58, magnet of relay 16 and to ground, the energization of the magnets of relays 15 and 16 resulting in the actuations of their respective armatures, from wire 58 through the armature of relay 16 to wire 59, thence to magnet of relay 17 and to ground, thus energizing the magnet of relay 17 and causing its armature to actuate, this actuation causing another circuit to be made from wire 59 through the armature of relay 17 to wire 60, thence to wire 61, armature of relay 55 to wire 62, through the coils of relay 63 to ground, thus causing the operation of relay 63; another circuit is now made from ground 64 through battery 65, wire 66, through armature of relay 63, wire 67, magnet of relay 68 and to ground at 69, thus actuating the armature of relay 68, there to remain until the parts are restored to normal; the operation of relay 68 reverses the positions of spring-contacts 70 and 71, connection being now broken between 70 and 72 and connection being made between 71 and 73. Another circuit makes as follows: wire 4 to wire 41, wire 74 through the armature of relay 54, to wire 75, through the coils of relay 51 and to ground, thus actuating the armature of relay 51.

The dash being now completed the armature of main-line relay 1, is actuated into the normal position and the following circuits

ensue: wire 5, through armature of relay 24, wire 34, through magnet 18 to ground, thus operating relay 18, which makes a circuit from wire 34, through the armature of relay 18, to wire 76, switch 77, wire 78, through magnet of relay 19, and to ground; the armature of relay 19 is actuated and makes another circuit from wire 78, branch wire 79, through the armature of relay 19 to wire 80 and through the magnet of relay 20 and to ground, this operates relay 20 and makes circuit from wire 80, branch 81, through the armature of relay 20 to wire 82, through the magnets of relays 21 and 22 and to ground, thus operating the relays 21 and 22. The operation of relay 22, makes the following circuit: from ground at 89, through the coils of relay 24 (the entrance-relay), to wire 90, through battery 91, through the armature of relay 22, wire 92, through the armature of relay 93, conductor 94 to spring-contact 95, wire 96 to spring-contact 97, wire 98, wire 99, spring-contact 100, wire 101, through type-bar magnet 102 to wire 103, wire 104, through armature of relay 29 to wire 106, through armature of circuit-making relay 28 to wire 107 and to ground at 108, thus restoring the entrance-relay 24 to normal position and effecting an energization of the type-bar magnet 102, and the corresponding type-bar is operated.

Immediately following the print, the parts are restored to normal in the following manner: when relay 21 is operated another circuit is made from wire 82 to wire 83, through the armature of relay 21 to wire 84, through magnet of relay 23 and to ground, thus operating relay 23 and the operation of relay 23 completes a restoring-circuit from ground 85, through battery 86, through armature of relay 23 to wire 87, thence through the restoring-coils of polar relays 39, 40, 46, 47, 54, 55, 43, 50, 51, 109, 110, 111, and 63 and to ground at 88. The operation of polar relays 109, 110, 111 and 63 to the normal position breaks the circuits controlling relays 93, 112, 113 and 68 and their respective springs actuate their armatures to the normal position. It will be understood however, that in the operation just described only one of these relays were operated, it being relay 68.

It will be seen that by following out the method previously described, a circuit may be completed through any one of the various type-bar magnets 25 at will, and through any one of the corresponding magnets in sets 26 and 27 after the proper operations are made with the circuit-making relays as explained.

I will now describe the operation of the circuits controlling the sets of printing and operating-magnets: if the set 26 is desired to be cut into circuit with the selecting-relays, four dashes will be required to effect

the purpose and the relays 93, 112, 113 and 68 will be operated and a circuit will be made as follows with the completion of the said four dashes, similarly as described in 5 the energization of type-bar magnet 102: from ground 89, through the coils of entrance-relay 24, wire 90, battery 91, through armature of relay 22, to wire 92, through the armature of relay 93, wire 94, wire 114, 10 spring-contact 115, wire 116, spring-contact 117, wire 118, spring-contact 119, through the magnet of circuit-making relay 28 and to ground, thus operating relay 28. If the same operations are now effected which re- 15 sulted in the energization of the type-bar magnet 102, in the set 25, as previously described, the circuit will be as follows: from spring-contact 100, wire 101, wire 126, type-bar magnet 125, wire 123, armature of relay 20 30 (circuit-making relay), wire 124, armature of circuit-making relay 28, wire 107 and to ground at 108, thus energizing the type-bar magnet 125, in set 26, which magnet corresponds with the type-bar magnet 102 in 25 set 25. To cut into circuit the third set 27, with the selecting-relays, three dashes are necessary to effect the proper operations of circuit-making relays 29, 30 and 31 and when said operations are accomplished the following 30 circuit will be made: from ground at 89, through the coils of entrance-relay 24, wire 90, through battery 91, armature of relay 22, wire 92, armature of selecting-relay 93, wire 94', wire 114, spring-contact 115, wire 116, 35 spring-contact 117, wire 118, wire 128, spring-contact 127, through the coils of the circuit-making relays 29, 30 and 31, to ground at 165, resulting in the operation of the three last-named relays, which will make 40 a circuit as follows, when it is desired to energize the type-bar magnet 131, in set 27, said type-bar magnet corresponding to the type-bar magnets 102 and 125 in sets 25 and 45 26, and assuming that the circuit has been operated similarly as previously described in the energization of type-bar magnet 102, so that spring-contact 100, is operated into engagement with wire 99: from spring-contact 50 100, wire 101, wire 126, wire 130, type-bar magnet 131, wire 132, armature of circuit-making relay 31 and to ground at 133, thus energizing type-bar magnet 131. To restore the sets 25, 26 and 27 to normal, it will be 55 necessary that the proper combination of operations be effected, similarly as previously described, which will result in the spring-contact 134 being brought into engagement with wire 135, which will result in the 60 operation of the circuit-making relays 28, 29, 30 and 31, which relays are connected in electrical series for simultaneous operation, via wires 160, 161, 162, 163, and 164 and to ground at 165. The armatures of all the 65 polar relays tend to remain in contact with whatever contact-point they are in contact

at the time. These relays are provided with a second or restoring-circuit for returning their armatures to the normal position.

In Fig. 2, I have shown mechanism for operating type-bars by electromagnets, the 70 parts there shown being an ordinary typewriter roll or platen 138, type-bars 139, connected by links 140, to armature-levers 141, adapted to be operated by the printing-magnets 142; but it will be understood that 75 I do not limit myself to any particular printing mechanism and that the mechanism of any of the well-known electrical typewriters may be used. Further, it will be understood that certain of the magnets 142, 80 may operate shift, spacing, and carriage-return mechanism such as are commonly used in electrical type-writers, such magnets acting directly or as relays to complete the circuit of other magnets. 85

In Figs. 3 and 4, I have shown a relay for operating a plurality of oppositely-opposed spring-contact connections, adapted to be operated by polar relays 110, 111 and 63, but it will be understood that I do not limit 90 myself to this particular type of spring-contact connection as such parts may be made in various ways. Referring to the parts, 68' is an armature-lever pivoted on support 146, said support having a base 147; 95 adjustable screws 150 and 150' are carried by supports 146 and 148, to limit the travel of the armature 68'. Screws 150 and 150' are adapted to carry wires 99 and 99'. Another support 149, carries two sets of op- 100 positely-opposed spring-plates, adapted for alternate engagement with screws 150 and 150'. Screws 151 and 151' are for holding wires 101 and 101'. A spring 157 holds the armature 68' normally in one position 105 and magnet 68 is adapted when energized to actuate the said armature into the abnormal position. Armature 68' is provided with insulation on its free end and oscillates between the screws 150 and 150' and being 110 placed between the spring-plates 100 and 100', said plates are brought into engagement with the screws 150 and 150' alter- 115 nately, thus making a plurality of connec- 120 tions by the actuation of one armature. 115

It will be obvious that my invention is susceptible of many variations and modifications without departing from the principles herein set forth, and I do not limit myself to the details of construction and arrangements of the parts herein illustrated and described.

The principal reason for transmitting messages by current pulses of alternately- 125 opposite direction is that polar instruments work better on a long line than do neutral instruments. When preferred, the main-line relay of the receiver may be a neutral relay, and in such case the transmitter need not be so constructed as to reverse current 130

polarity. This arrangement is shown in Fig. 1^a.

It will be understood that the main-line relay of the receiver may be connected in series with the receiving relay of a duplex or quadruplex, thus enabling my receiver to operate in connection with such systems.

What I claim is—

1. In a printing-telegraph, the combination with an electrically-controlled plurality of circuit-forming relays comprising relays arranged for successive operation the extreme relays of which are operated only by long pulses, of a plurality of dash-circuits controlled by said circuit-forming relays, a plurality of dash-relays, one for each such circuit, a plurality of selecting-circuits controlled by said dash-relays, selecting-relays one controlled by each dash-relay and having contacts arranged in clusters in geometrical progression, each such selecting-relay but the last controlling the circuits through the contacts of the relay of the next cluster, printing or operating-magnets in circuits connected to the contacts of the selecting-relay of the last cluster, a plurality of said operating-magnets being magnets of circuit-making relays, said printing and operating-magnets arranged in sets, said sets of printing and operating-magnets controlled in circuits controlled by the contacts of said circuit-making relays, a restoring-relay, a restoring-circuit operated thereby passing through circuit-forming relays and through said dash-relays, and means operated by the circuit-forming relays for completing a circuit through contacts of the selecting-relays to the selected printing or operating-magnet, and means for operating the restoring-relay.

2. In a printing-telegraph, the combination with an electrically-controlled plurality of circuit-forming relays comprising polar relays and neutral relays, said neutral relays comprising relays arranged for successive operation, the extreme relays of which being controlled only by long pulses, of a plurality of dash-circuits controlled by the polar circuit-forming relays, and a plurality of corresponding polar dash-relays, one for each such circuit, said polar relays having restoring-coils, a plurality of selecting-circuits controlled by said dash-relays, selecting-relays one in each such selecting-circuits and having contacts arranged in clusters, contacts of each cluster being connected to contacts of the succeeding cluster, printing and operating-magnets controlled by said selecting-relays, a restoring-relay and a circuit therefor including the restoring-coils of the dash-relays and the polar circuit-forming relays, and means operated by the neutral circuit-forming relays, for completing a circuit through the contacts of the selecting-relays to the se-

lected printing or operating-magnet, and means for operating the restoring-relay.

3. In a printing-telegraph, the combination with an electrically-controlled plurality of circuit-forming relays, comprising a plurality of relays arranged for successive operation, the extreme relays of which are controlled only by relatively long pulses, of a plurality of dash-circuits arranged to be formed successively by the contacts of said circuit-forming relays, and a corresponding plurality of dash-relays, one such relay in each such circuit, a plurality of selecting-relays corresponding to and controlled by the dash-relays, said selecting-relays having contacts arranged in clusters, the contacts of said clusters arranged and connected in geometrical progression, printing and operating-magnets, controlled by the contacts of the last cluster, said printing and operating-magnets arranged in sets, polar circuit-making relays having magnets included in said operating-magnets, said sets controlled in circuits passing through contacts of said circuit-making relays, a main-line relay, a polar entrance-relay co-operating with said main-line relay for controlling all said relays, means for completing a circuit through contacts of the selecting-relays and the selected printing or operating-magnet and for restoring the entrance-relay, and means controlled by one of said extreme relays for restoring the dash-relays and the operated circuit-forming relays.

4. In a printing-telegraph, the combination with an electrically-controlled plurality of circuit-forming relays comprising relays arranged for successive operation two of the extreme relays of which are operated only by relatively long pulses, of a plurality of dash-circuits arranged for formation successively by the contacts of a plurality of said circuit-forming relays, a corresponding plurality of dash-relays, one such relay in each such dash-circuit, a plurality of selecting-relays having contacts arranged in clusters, said selecting-relays corresponding to and controlled by the dash-relays, the contacts of each cluster succeeding the first connected to contacts of the preceding cluster, printing and operating-magnets controlled by the contacts of the last cluster, a relay for completing a circuit through contacts of the selecting-relays, and a restoring-relay and means operated thereby for restoring the dash-relays and the operated circuit-forming relays, both controlled by the circuit-forming relays.

5. In a printing-telegraph, the combination with an electrically-controlled plurality of circuit-forming relays comprising polar and neutral relays, of a plurality of dash-circuits, said polar relays having contacts arranged to control said dash-circuits successively, a corresponding plurality of polar

dash-relays each in circuit with one of said dash-circuits, a plurality of selecting-relays having contacts arranged in clusters, said selecting-relays corresponding to and controlled by the dash-relays, printing and operating-magnets in circuits controlled by the contacts of said selecting-relays, a print-relay and a restoring-relay, the former controlling the circuit through contacts of the

5 selecting-relays and printing or operating-magnets, the latter controlling a restoring-circuit of the dash-relays and the polar circuit-forming relays, both the print and restoring-relays controlled by the neutral relays comprised in the circuit-forming relays.

6. In a printing-telegraph, the combination of an electrically-controlled plurality of circuit-forming relays comprising polar 20 and neutral relays, polar dash-relays having separate actuating-circuits controlled in dash-circuits by said circuit-forming relays and having also a restoring-circuit, said restoring-circuit also embracing the polar circuit-forming relays, selecting-relays having contacts connected in geometrical progression, each such selecting-relay operated by a circuit controlled by one of said dash-relays, printing and operating-magnets controlled 25 by the selecting-relays, a print-relay and restoring-relay, both in circuits controlled by said neutral relays.

7. In a printing-telegraph, the combination with a main-line relay, of a plurality of 30 circuit-forming relays comprising polar and neutral relays, the said neutral relays comprising relays arranged for operation successively and the extreme relays of which are controlled by relatively long pulses, an entrance-relay and a dash-completing relay controlled by said main-line relay, branch circuits controlling said circuit-forming relays and controlled by said entrance-relay and said main-line relay, a plurality of dash-circuits controllable successively by the 35 contacts of the polar circuit-forming relays, said dash-completing relay controlled only by long pulses and controlling the completion of said dash-circuits, a plurality of dash-relays controlled by said dash-circuits, one such dash-relay in each such dash-circuit, selecting-relays corresponding each to one of said dash-relays, each such selecting-relay controlled by a circuit controlled by the corresponding dash-relay, printing and operating-magnets controlled by the selecting-relays, said printing and operating-magnets arranged in sets, a plurality of said operating-magnets being magnets of circuit-making 45 relays, said circuit-making relays controlling said sets of printing and operating-magnets, and means operated by said neutral relays for completing a circuit through contacts of the selecting-relays to whichever 50 of the printing or operating-magnets is se-

lected and for restoring the entrance-relay, and means for restoring the dash-relays and the polar circuit-forming relays.

8. In a printing-telegraph system, the combination with a transmitter constructed and arranged to produce in a line-circuit when said transmitter is operated a characteristic signal corresponding to each letter of the alphabet and other characteristic signals corresponding to each character of a code, of a receiving instrument having a separate printing or operating-magnet for each letter of the alphabet and for each character of the code, said printing and operating-magnets arranged in sets, a plurality of said operating-magnets being magnets of circuit-making relays, said circuit-making relays controlling said sets of printing and operating-magnets, selecting-relays having their contacts connected in geometrical progression, circuit-forming relays controlling the circuits formed through said contacts for selecting and energizing the particular printing or operating-magnet corresponding to whichever letter or characteristic signal is transmitted, and means controlled by a single line-circuit connecting the transmitter and receiver, controlling the action of said selecting and circuit-forming relays; and the said line-circuit.

9. In a printing-telegraph system, the combination with a transmitter constructed and arranged to produce in a line-circuit when said transmitter is operated a characteristic signal corresponding to each letter of the alphabet and other characteristic signals corresponding to each character of a code, of a receiving instrument having a separate printing or operating-magnet for each letter of the alphabet and for each character of the code, an electrically-controlled plurality of circuit-forming relays comprising relays operating *seriatim*, selecting-relays in branch circuits controlled by said circuit-forming relays and comprising relays having contacts connected in geometrical progression, said relays arranged to select the particular magnet corresponding to whichever letter or characteristic signal is transmitted, and means controlled by a single line-circuit for controlling said circuit-forming relays; and the said line-circuit.

10. In a printing-telegraph system, the combination with a transmitter constructed and arranged to produce in a line-circuit 120 when said transmitter is operated a characteristic signal corresponding to each letter of the alphabet and other characteristic signals corresponding to each character of a code, of a receiving instrument having printing or operating-magnets corresponding to the several characteristic signals, an electrically-controlled plurality of circuit-forming relays comprising relays operating *seriatim*, dash-relays controlled by said circuit-form-

ing relays, selecting-relays corresponding to the several dash-relays, each such relay in a circuit controlled by one such dash-relay, said selecting-relays having contacts in clusters connected in geometrical progression, 5 said printing and operating-magnets connected with the contacts of the final cluster, and means for operating said circuit-forming relays controlled by a single line-circuit connecting the transmitter and receiver; and 10 the said line-circuit.

11. In a printing-telegraph system, the combination with a transmitter constructed and arranged to produce in a line-circuit when said transmitter is operated a characteristic signal corresponding to each letter of the alphabet and other characteristic signals corresponding to each character of a code, of a receiving instrument having printing and operating-magnets corresponding to the several characteristic signals, an electrically-controlled plurality of circuit-forming relays, comprising polar and neutral relays, said neutral relays comprising relays 20 arranged for operation successively, the extreme relay of which being arranged for operation by long pulses only, dash-relays controlled by said polar circuit-forming relays, selecting-relays corresponding to the several 25 dash-relays, each such selecting-relay in a circuit controlled by one such dash-relay, the contacts of the selecting-relays connected in geometrical progression, and the last contacts of the progression connected to the 30 several printing and operating-magnets, a plurality of said operating-magnets being magnets of polar circuit-making relays, said printing and operating-magnets arranged in sets, said sets controlled in circuits through 35 contacts of said circuit-making-relays, a dash-completing relay for completing the circuits controlling the dash-relays, a main-line relay controlling the circuit-forming relays and the dash-completing relay, and a line-circuit connecting the transmitter and 40 said main-line relay of the receiver.

12. In a printing-telegraph system, the combination with a transmitter constructed and arranged to produce in a line-circuit when said transmitter is operated a characteristic signal corresponding to each letter of the alphabet and other characteristic signals corresponding to each character of a code, of a receiving instrument having printing and operating-magnets corresponding to the several characteristic signals, an electrically-controlled plurality of circuit-forming 50 relays comprising polar relays and two sets of neutral relays, the relays in each of 55 said sets of neutral relays arranged for successive operation, the extreme relays of each set being operated only by relatively long pulses, said polar circuit-forming relays controlling dash-circuits successively, dash- 60 relays corresponding in number to the num- 65

ber of dash-circuits and each controlled by one such dash-circuit, selecting-relays corresponding to the several dash-relays, each such relay in a circuit controlled by one of said dash-relays, the contacts of the selecting-relays connected in selective circuits and the contacts of the final selecting-relay connected with the several printing and operating-magnets, a plurality of said operating-magnets being magnets of circuit-making 70 relays, said printing and operating-magnets arranged in sets, said sets controlled in circuits through the contacts of said circuit-making relays, a main-line relay, an entrance-relay, said entrance-relay co-operating with said main-line relay for controlling the circuits controlling the circuit-forming relays, a dash-completing relay operative only by pulses of one character, a print-relay and a restoring-relay, said print-relay arranged 75 when operated to complete a selected circuit through contacts of the selecting-relays and the printing or operating-magnets selected thereby, said restoring-relay arranged when operated to restore the dash-relays and the polar circuit-forming relays, the relays comprising one of the sets of the neutral relays being operated by the final pulse of each signal for operating said print-relay and restoring-relay; and a line-circuit connecting 80 said transmitter and the main-line relay of the receiver.

13. In a printing-telegraph, the combination with a plurality of printing or operating-magnets, of a plurality of selective circuits for controlling the same, selecting-contacts in said circuits arranged in progression, selector mechanism responsive to successive electrical impulses of various numbers and arranged to control said contacts to establish a selected circuit and then to complete and energize said selected circuit in response to the final impulse irrespective of the number of impulses.

14. In a printing-telegraph, the combination with a plurality of printing or operating-magnets, of a plurality of selective circuits for controlling the same, selecting-contacts in said circuits arranged in clusters, the number of contacts of each succeeding cluster increasing progressively, electromagnets for controlling the contacts of said clusters, selector mechanism responsive to successive electrical impulses of various numbers and arranged to control the circuits of said electromagnets to establish a selected circuit through said contacts and then to complete and energize said selected circuit in response to the final impulse irrespective of the number of impulses.

15. In a printing-telegraph, the combination with a plurality of printing or operating-magnets, of a plurality of selective circuits for controlling the same, selecting-contacts in said circuits arranged in pro-

gression, a plurality of selecting-relays controlling said contacts, and a plurality of circuit-forming relays comprising relays operating *seriatim* and connecting circuits co-operating with said selective circuits and selecting-relays to establish and complete a selected circuit through said contacts.

16. In a printing-telegraph, the combination with a plurality of printing or operating-magnets, of a plurality of selective circuits for controlling the same, selecting contacts in said circuits arranged in clusters, the number of contacts of each succeeding cluster increasing progressively, electromagnets for controlling the contacts of said clusters, dash-relays controlling the circuits of said electromagnets, dash-circuits including said dash-relays, a plurality of circuit-forming relays controlling said dash-circuits, and means responsive to electrical impulses of different characters for establishing circuits through said relays and completing a selected circuit through one or more of said contacts.

17. In a printing-telegraph, the combination with a plurality of printing or operating-magnets, of selective circuits for controlling the same, and a plurality of circuit-forming relays comprising a retarding-set having relays operating successively, circuits co-operating with said circuit-forming relays and the selective circuits for completing a selected circuit, and means controlled by an extreme relay of said successively operated relays for energizing the selected circuit.

18. In a printing-telegraph, the combination with a plurality of printing or operating-magnets, of selective circuits for controlling the same, a plurality of circuit-forming relays comprising relays operating successively, circuits co-operating with said circuit-forming relays and the selective circuits for completing a selected circuit, a restoring-circuit for at least a number of said circuit-forming relays, extreme relays of said successively operated relays operating to control the energization of the selected circuit and said restoring-circuit.

19. In a printing-telegraph, the combination with a plurality of printing or operating-magnets, selective circuits for controlling the same, a main-line relay responsive to successive electrical impulses, and means controlled by said main-line relay in response to the second impulse or any impulse alternate thereto when prolonged for completing and energizing the selected circuit.

20. In a printing-telegraph, the combination with a plurality of printing or operating-magnets, of selective circuits for controlling the same, contacts arranged in progression in said circuits, selecting-relays controlling said contacts, dash-relays controlling the circuits of said selecting-relays,

a main-line relay responsive to successive electrical impulses, means controlled by said main-line relay in response to alternate impulses when prolonged for energizing a dash-relay, and means controlled by the intermediate alternate impulses when prolonged for completing and energizing the selected circuit.

21. A printing telegraph comprising electrical printing and operating mechanism, selecting mechanism therefor, controlling magnets and circuits for said selecting mechanism, a main-line relay, branch circuits controlled by alternate movements of the armature of said main-line relay, and individual relays operative in predetermined sequence by the second and succeeding movements of said armature to prepare said controlling circuits.

22. A printing telegraph comprising electrical printing and operating mechanism, selecting mechanism therefor, controlling magnets and circuits for said selecting mechanism, a main-line relay, branch circuits controlled alternately by said main-line relay, and individual relays operative in predetermined sequence in response to the second impulse and succeeding impulses thereafter through said main-line relay to prepare said controlling circuits.

23. A printing telegraph comprising a plurality of printing or operating magnets, selective circuits for the same, selecting contacts in said circuits, controlling magnets and circuits for said selecting contacts, a main-line relay, branch circuits controlled alternately by said main-line relay, and individual relays operative in predetermined sequence in response to the second impulse and succeeding impulses thereafter through said main-line relay to prepare said controlling circuits.

24. A printing telegraph comprising electrical printing and operating mechanism, selecting mechanism therefor, controlling magnets and circuits for said selecting mechanism, a main-line relay, branch circuits controlled by alternate movements of the armature of said main-line relay, individual relays operative in predetermined sequence by the second and succeeding movements of said armature to prepare said controlling circuits, and means for energizing the prepared controlling circuit.

25. A printing telegraph comprising electrical printing and operating mechanism, selecting mechanism therefor, controlling magnets and circuits for said selecting mechanism, dash relays controlling the circuits of said controlling magnets, a main-line relay, branch circuits controlled by alternate movements of the armature of said main-line relay, and individual relays operative in predetermined sequence by the second and succeeding movements of said

armature and coöperating with said dash relays to prepare said controlling circuits.

26. A printing telegraph comprising electrical printing and operating mechanism, 5 selecting mechanism therefor, controlling magnets and circuits for said selecting mechanism, a main-line relay, branch circuits controlled by alternate movements of the armature of said main-line relay, and 10 individual relays operative in predetermined sequence by the second and succeeding movements of said armature to prepare said controlling circuits, the last of said individual relays to operate being arranged 15 to open the actuating circuit of the preceding relay.

27. A printing telegraph comprising a plurality of printing or operating magnets, selective circuits for said magnets, selecting contacts in said circuits, controlling magnets and circuits for said selecting contacts, dash relays controlling the circuits of 20 said controlling magnets, a main-line relay, branch circuits controlled by the armature 25 of said main-line relay, individual relays

operated *seriatim* by the succeeding movements of said armature and coöperating with said dash relays to prepare said controlling circuits, means for energizing the prepared controlling circuit, and means for 30 energizing the selected printing or operating circuit.

28. A printing telegraph comprising electrical printing and operating mechanism, selecting mechanism therefor, controlling 35 magnets and circuits for said selecting mechanism, a main-line relay having an armature to control said controlling circuits, and individual relays operated in selected sequence by impulses moving said armature in one direction to prepare a controlling circuit, and in the other direction to complete and energize the selected circuit.

In testimony whereof I affix my signature in the presence of two witnesses.
